United States Patent Office.

W. H. LAUBACH, OF PHILADELPHIA, PENNSYLVANIA.

Letters Patent No. 73,816, dated January 28, 1868.

IMPROVEMENT IN GAS-ENGINES.

The Schedule referred to in these Letters Patent and making part of the same.

TO ALL WHOM IT MAY CONCERN:

Be it known that I, W. H. LAUBACH, of the city of Philadelphia, in the county of Philadelphia, in the State of Pennsylvania, have invented a new and useful Improvement in "Gas-Engines;" and I do hereby declare that the following is a full and exact description thereof, reference being had to the accompanying drawings, making a part of this specification, in which—

Figure 1, plate A, is a plan, with some parts in section, of my machine.

Figure 1, plate B, is a sectional elevation of my machine.

Figure 2, plate B, is a sectional elevation of the check gas-valve.

Figure 3, plate B, is a plan view of the said valve.

Figure 4, plate B, is a sectional elevation of the gas-aperture or gas-igniting tubes.

Figure 5 is a sectional plan of said aperture.

The nature of my invention consists in a gas-machine, in which the igniting flame is made to enter directly the cylinder, thus passing through the gas, and, coming in contact with its inflammable portion, will ignite and explode it.

To enable others skilled in the art to make and use my invention, I will now proceed to describe its construction and operation.

C C is the cylinder, made out of metal or material to suit; P I is the piston, with the usual packing, &c.; P R is the piston-rod; P, the packing for said rod, in head H of the cylinder; K is the gas-feeding pipe, and K' the exhaust or discharge-pipe; S V is the inlet or gas-feeding slide-valve; S' V', the exhaust slide-valve; S P and S' P' is a water-chamber all round the cylinder, and which is filled up to prevent the cylinder from being overheated; T is an inflexible tube, of small diameter, passing through the centre of cylinder-head H', and secured to centre of piston P I; P' is the gas-tight packing of said tube T, in head H' of P I. T is drawn in and out of the cylinder C by the in-and-out movement of the piston to which it is attached. T' is another tube, equal in diameter to T, and parallel to piston-rod P R, and passes through head H of C. Although not secured to the piston, the end of T, inside cylinder C, comes close to the face of the piston, so that when said piston is drawn close to head H of C, it (the end of T') will still be in the cylinder C. P'' is the gas-tight packing T' runs through. The outer end of T' is connected with the piston-rod's head, and, therefore, T' has the same movement and stroke as P R. The outer ends of T and T' are alternately closed by check-valves C V, for the purpose hereinafter shown. P O is a gas-pipe, set alongside of, or under, or in any suitable position near cylinder C, and of a length about equal to that of said cylinder. p g and p' g' are two India-rubber, gutta-percha, or any suitable material tubes, respectively connecting the outer ends of T and T' with the corresponding end of P O. The length of said flexible connecting-tubes must be such that when the machine is running, p g or p' g', or both, will in nowise check or interfere with the stroke of either tubes T or T'. The outer end of tube T' is connected with rod P R by being secured to said rod cross-head C H, so that both run parallel. Inside both outer ends of tubes T and T', and near the connection with elastic tubes p g and p' g', are two check-valves, for the purpose aforesaid. 1 and 1' are two upright gas-burners, respectively set into both ends of pipe P O, and high enough that their heads will be close, respectively, to both tubes T and T', and near packings P' and P''. Two apertures or small holes, A M and A' M', are made into pipes T and T', for purposes hereinafter shown. Figs. 4 and 5 show, on enlarged scale, the special construction of said apertures A M and A' M', which is as follows: In the centre of T and T' are inserted two smaller tubes, t m, at a certain distance from A M and A' M', and between said apertures and the respective outer ends of T and T'. The end of t m reaches the centre of apertures A M and A' M', and is made so as to end in a tapering very small mouth, t a. The said tubes t m are encased, so that the gas coming through T and T' can reach apertures A M and A' M' but through mouths t a. I make t m of metal, or any material to suit, such, perhaps, as soapstone, which wears better, as it cannot rust, which always deteriorates the mouth t a.

Thus constructed, my machine is now ready for use. The inlet-valve is open, the piston is moved one-half of the cylinder. This movement draws in the inflammable gas. The inlet-valve then closes, and at the same time the aperture A M, in pipe T, enters the cylinder. In passing gas-burner B, where the gas has been lit, this lights the gas escaping through t a in aperture A M, so that when A M, as aforesaid, enters the cylinder,

the flame or lit jet in A M ignites the inflammable gas in the cylinder. Should the stratum of gas, the flame A M, come first in contact, it will not be in condition to be ignited. As it (the flame) will pass through many different strata it must meet one which will ignite and explode. The explosion puts out the flame in A M, but when A M comes out, it will again be relit by burner B. Tube T' and aperture A' M' act in a similar way.

I have endeavored to show the principle or mode of passing the igniting flame directly through the inflammable gas in the cylinder, which I have essayed in various ways, and believing this the best, what I claim as my invention, and desire to secure by Letters Patent of the United States, is—

The combination and arrangement of the devices, as herein set forth, whereby the igniting flame is caused to pass directly through the inflammable gas, inside of the cylinder, substantially as herein set forth and described.

W. H. LAUBACH.
